UNITED STATES PATENT OFFICE.

FRANK S. LOVITT, OF RAVENNA, NEBRASKA.

DERRICK.

1,178,865.

Specification of Letters Patent. Patented Apr. 11, 1916.

Application filed May 29, 1913. Serial No. 770,666.

To all whom it may concern:

Be it known that I, FRANK S. LOVITT, citizen of the United States, residing at Ravenna, in the county of Buffalo and State 5 of Nebraska, have invented certain new and useful Improvements in Derricks, of which the following is a specification.

This invention relates to improvements in derricks, and the object thereof is first 10 to provide a simple and cheap device wherein the several frame parts may be easily disconnected for changing the location of the device, second, to provide a rotatable boom and support therefor whereby the article 15 lifted or elevated may be swung or rotated to any degree or angle of a complete circle to facilitate the loading and unloading of various types of vehicles or cars, and third, to provide a derrick capable of being operated 20 by a single person thus saving time to a certain extent and materially reducing the cost of labor.

The invention still further resides in the provision of a balanced rotatable boom 25 wherein means is provided for supporting the same upon a rotatable stand or tower, the latter having a drum or windlass mounted thereupon for operating ropes arranged over pulleys carried by the said boom.

30 The above and additional objects are accomplished by such means as are illustrated in their preferred embodiment in the accompanying drawings, described in the following specification and then more particularly 35 pointed out in the claim which is appended hereto and forms a part of this application.

In describing my invention in detail reference will be had to the accompanying drawings wherein like characters denote like 40 or corresponding parts throughout the several views; and in which:—

Figure 1 is a perspective view of a derrick constructed in accordance with my invention illustrating the application thereof; 45 Fig. 2 is a top plan view; and Fig. 3 is a front elevation.

Before proceeding with the description of the drawings, I desire to call particular attention to the fact that while I have evolved 50 my invention with particular reference to a hand operated device, the same may be readily utilized or employed in connection with any suitable source of motive power for greatly increasing the lifting power of the derrick.

Referring now to the drawings, wherein

is illustrated the preferred form of my invention the numeral 1 designates a base plate adapted to be secured to the ground in any suitable manner, the said plate being provided with a smooth upper face upon which is pivotally arranged by means of a pivot pin 2, an upright stand or tower, designated in its entirety by the numeral 3. The said tower comprises a base plate 4 through which the pivot pin 2 extends and sides 5, the latter being converged upwardly from the said plate to a suitable block 6 the latter adapted to receive a pivot pin 7 depending from the converged extremity of the derrick frame 70 portion 8. Brace beams 9 are arranged upon the tower 3 and extend from one to the other of the sides thereof and support the said sides in proper spaced relation for a purpose to be hereinafter fully described. Secured to 75 the tower sides 5 adjacent the converged end thereof I provide a balanced boom 10 extending transversely of the tower and supported thereupon by means of ropes 11 secured as at 12 to the tower sides and extending over one extremity of the boom 10, the said extremity extending beyond the tower 3 as is clearly shown in Fig. 1 of the drawings. The ropes 11 continue from the extremities of the boom 10 upwardly and 80 over the converged extremity of the tower 3, from which point they further extend to the converged end of the said boom 10 where they are securely fastened, the said boom being substantially V-shaped to conform to 85 the outline or shape of the tower 3. A block 13 is interposed between the converged extremities of the boom 10 into which an eye 14 is screwed or otherwise secured, the said block also supporting a pulley 15 over which 90 the guy rope 16 of the derrick is arranged in a manner to subsequently appear.

Mounted between the tower sides 5 near the base 4 thereof is a shaft 17, having a hand wheel 18 mounted upon one end thereof, the 100 said wheel being arranged upon the exterior of the tower for winding or rotating the shaft during the operation of the device. One end of the guy rope 16 is secured to the shaft, from which point the said rope extends upwardly and over a pulley 19 depending from the boom 10 between the tower sides 5 from which point the rope extends forwardly to the pulley 15 and downwardly 105 therefrom to a third pulley 20 over which it passes to extend to the eye 14 where it is 110 permanently secured. By this arrangement

it will be seen that the said pulley 20 is raised or lowered according to the rotation of the shaft 17 and by providing the pulley 20 with a rope 21 for securing the article 5 to be lifted or elevated, the desired result is accomplished.

Uprights 22 arranged in spaced relation are disposed adjacent the tower 3 and are braced by suitable beams 23, the said uprights 10 having the extremities of the frame portion 8 secured thereto for effecting a support therefor, the latter carrying the pivot pin 7 by means of which the tower 3 is supported vertically upon the base 1 of 15 the derrick.

A latch member 24 is mounted upon the tower 3 at one side thereof, the said member adapted to engage the base 1 for retaining the tower against rotation when desired. To 20 insure a secure locking of the said tower against rotation, the latch member 24 is provided with a sharpened or pointed end adapted to bite into the base and thus prevent movement of the tower independent 25 thereof.

Having described in detail the construction of the device, it now remains to set forth the operation of the same. After fastening the article to be lifted to the pulley 30 20 by means of the rope 21, the windlass 17 is rotated by means of the hand wheel 18 secured thereto, the winding or rotation of the said windlass causing the pulley 20 to be elevated by means of the rope 16 arranged 35 thereover. After elevating the article to the desired height the entire tower may be rotated upon the base 1 by means of the said handle 18 thus swinging the article to any degree or angle of a circle desired, thereby 40 facilitating to a great extent the loading and unloading of cars, vehicles or the like,

by the use of a derrick constructed as above described.

In reduction to practice, I have found that the form of my invention, illustrated in the 45 drawings and referred to in the above description, as the preferred embodiment, is the most efficient and practical; yet realizing that the conditions concurrent with the adoption of my device will necessarily vary, 50 I desire to emphasize the fact that various minor changes in the details of construction, proportion and arrangement of parts may be resorted to, when required, without sacrificing any of the advantages of my invention, as defined in the appended claim.

Having thus fully described my invention, what I claim as new and desire to secure by Letters Patent, is:—

A derrick including a substantially V-shaped upright rotatable frame, a substantially V-shaped boom affixed to the frame, a rigid connection between the boom and the frame at a point intermediate the ends of the former and adjacent the top of the latter, brace means for the boom secured at one end to the frame adjacent the diverged end thereof and at its opposite end to the converged end of the boom, the said brace means engaging with the top of the frame and with the diverged end of the boom, a brace beam for the upright frame, and a means attached to the converged end of the boom for raising and lowering articles relatively thereto.

In testimony whereof I affix my signature in presence of two witnesses.

FRANK S. LOVITT.
